(57) **CLAIM**

I claim the ornamental design for an egg-carrier device, as shown and described.

DESCRIPTION

FIG. 1 is a first side view of a first component of an egg-carrier device embodying the design;

FIG. 2 is a second side view of the first component shown in FIG. 1;

FIG. 3 is a second side view of a second component of the egg-carrier device that may be combined with the first component of FIG. 1;

FIG. 4 is a first side view of second component shown in FIG. 3;

FIG. 5 is a top view of the second component shown in FIG. 3;

FIG. 6 is a top view of the first component shown in FIG. 1; FIG. 7 is a bottom view of the second component shown in FIG. 3;

FIG. 8 is a bottom view of the first component shown in FIG. 1;

FIG. 9 is an enlarged end view of the egg carrier; and, FIG. 10 is a perspective view of the first and second components positioned next to each other.

The components are being shown separately in FIGS. 1 through 4 for convenience of illustration.
